LOUIS M. DANKLEFS AND FRED E. DANKLEFS, OF LOS ANGELES, CALIFORNIA.

METHOD OF MAKING BOXES.

Application filed June 26, 1923. Serial No. 647,881.

To all whom it may concern:

Be it known that LOUIS M. DANKLEFS and FRED E. DANKLEFS, citizens of the United States, residing at Los Angeles, in the 5 county of Los Angeles and State of California, have invented certain new and useful Improvements in Methods of Making Boxes, of which the following is a specification.

10 This invention relates to boxes having a bead at the upper edge of the box proper, and a cooperating recess in the lower edge of the lid, adapted to be received over said bead for properly positioning the lid upon 15 the box, the construction being particularly applicable to wooden boxes having hinged lids.

It is the object of the invention to provide correspondingly curved sides upon the 20 cooperating bead and recess of the box and lid, in order that the hinged lid may be swung to closed position without abutment of said bead against the wall of said recess, and in order that the correspondingly 25 curved sides of the bead and recess will lie against one another so as to form a snug fit when the lid is closed.

It is a further object of the invention to provide a box having side walls interlocked 30 at their ends, as for example by dove-tail joints, with the inner sides of said ends of the side walls cut at angles of 45°, so that abutment of said angled ends at the corners of the box, will positively square the structure.

It is a still further object of the invention to reduce the number of parts in the improved box, by cutting the side walls thereof, so as to form the bead at the upper edge 40 of the box proper as an integral part of the same.

It is a still further object of the invention to reduce to a minimum the number of operations in the manufacture of the improved box, by cutting the recess which is at the lower edge of the lid, in the strips from which the side walls of the box are to be constructed, then cutting the ends of said strips so that they may be assembled to 50 form the side walls of the box, without said recesses extending through the interlocking ends of said strips at the corners of the box, and after fixing the top and bottom of the box upon the assembled side walls, cutting 55 through said walls with a blade adapted to separate the lid from the box proper, and

at the same time form the bead at the upper edge of the latter.

It is a still further object of the invention to provide for cutting a molding upon 60 the sides and top of the box during the operation of cutting the lid from the box proper and forming the bead at the upper edge thereof.

The invention will be readily understood 65 from the following description of the accompanying drawings, in which:

Fig. 1 is a vertical section through the cutting apparatus, showing the method of forming the lid recesses in the strips from 70 which the side walls of the box are constructed.

Fig. 2 is a fragmentary vertical section through the cutting apparatus, showing the method of cutting the ends of the recessed 75 side strips.

Fig. 3 is a horizontal section through a corner of the assembled side strips.

Fig. 4 is a perspective view, partly broken away, showing the top and bottom of the 80 box mounted on the assembled side strips, with the lid partly cut from the box proper.

Fig. 5 is a vertical section through the cutting apparatus, showing the blade for cutting through the side walls of the as- 85 sembled box.

Fig. 6 is a vertical section through the box with the lid swung open.

Fig. 7 is a view similar to Fig. 5, showing a modified form of blade adapted to 90 cut a molding upon the box.

The improved box consists of a lid having side walls 1 and top 2, and a box proper having side walls 3 and bottom 4. The respective sides of the lid and box may be connected by dove-tail joints 5, and the lid is preferably hinged to the box at one side 95 thereof as shown at 6.

A cooperating bead and recess are formed at the upper edge of the box and at the 100 lower edge of the lid respectively, and are arranged to permit free swinging of the lid to closed position, while forming a snug fit when the lid is closed.

The apparatus employed in the manufacture of the improved box includes novel cutting blades, which in the present instance are shown as detachably mounted in a rotatable cutter head, said head being adjustable with relation to a support upon which 105 the parts of the box are held during the cutting thereof.

The frame of the apparatus is shown as including a cylinder 7 having a work support 8 mounted thereon. A rotatable shaft 9 extends through said cylinder and above the work support, and is journaled in a bearing 10 adapted to be adjusted longitudinally of cylinder 7 and fixed in desired position by a set screw 11. The shaft may be rotated by any suitable means, shown as a pulley 13 on said shaft, having a power belt 14 received thereon and driven by a suitable source of rotary movement (not shown).

The shaft 9 has a threaded end 15 forming a shoulder 16 above the work support, and discs forming a cutter head 17 are received on the end of the shaft and are clamped against shoulder 16 by a nut 18. The adjacent faces of the discs are transversely slotted as shown at 19, and the shanks 20 of the various cutting blades are adapted to be clamped in said slots by tightening nut 18, with the cutting edges of the blades projecting radially beyond the cutter head.

In constructing the improved box, strips of material, preferably of wood, which are of a length to form the sides of the box and lid, and which are of a width slightly greater than the combined height of side walls 1 and 3, are recessed along one of their sides by moving said strips along the rotatable cutter head 17 having the cutting blade shown in Fig. 1 mounted therein.

The recesses are formed at the desired height in the strips, by resting the lower edges of said strips upon work support 8, the rotatable cutter being vertically adjusted relative to said work support, by longitudinally adjusting bearing 10 in cylinder 7, so that the lower side of the cut will be spaced from the upper edge of the strips, the desired width of side walls 1; and the depth of the cut is limited by abutment of the strips of material against the periphery of cutter head 17, the cutting edges of the blade projecting beyond the cutter head so as to cut recesses extending approximately half way through the strips.

The cutting blade shown in Fig. 1 has a straight cutting edge 21 at the bottom thereof parallel to the work support 8, and a convex cutting edge 22 curving upwardly and rearwardly from the front end of edge 21, so that said blade will cut a recess in the strips of material having straight lower side 23 and concave upper side 24, as shown in Fig. 4.

The ends of the recessed strips are then moved along the cutting apparatus with the blade shown in Fig. 2 mounted therein, said blade having a cutting edge 25 arranged at an angle of 45° to the work support 8.

The non-recessed surfaces of the strips rest upon the work support, with the cutter head vertically adjusted relative thereto, so

that cutting edge 25 will make a cut of 45°, as shown at 26, in the recessed surfaces of the strips at the ends thereof, with said cuts extending into said strips only to the depth of the recesses previously formed therein. 70

The movement of the strips toward the cutter is suitably limited so that the cutting edge 25 will inwardly space the angular cuts 26 from the ends of the strips, a distance equal to the non-recessed thickness of 75 said strips.

The ends of the strips extending beyond the angular cuts 26 which are thus formed in the inner surfaces of said strips, are then dove-tailed in the usual manner, and the strips are assembled to form the side walls of a rectangular box structure as shown in Fig. 3, with the dove-tailed ends interlocking to form joints 5 and the recessed sides 85 of the strips positioned at the inside of the box.

The angular cuts 26 of the two strips co-operating to form a corner of the box will thus abut so as to square said corner, and the recesses in the strips at the inside of the 90 box will not extend through the dove-tail joints 5 at the outer sides of the corners of the box.

When the side walls of the structure have been assembled as thus described, top 2 and bottom 4 are fixed thereon as shown in Fig. 4. Cuts are then made through the walls of the box from the outside thereof, by moving the box along cutter head 17 having the blade shown in Fig. 5 mounted therein. 100

This cutting blade has a straight upper cutting edge 27 parallel to work support 8, and a vertical cutting edge 28 depending for a short distance from the front end thereof, with a concave cutting edge 29 105 spaced rearwardly from the front cutting edge at the lower side of the blade and curving rearwardly and downwardly so as to terminate in a rearwardly extending cutting edge 30 parallel to cutting edge 27. 110

The cut made by the blade as thus described, may be properly positioned on the walls of the box, by resting the bottom of the box upon work support 8 during the cutting operation, and adjusting the cutter head relative to the work support as previously described, the cutter head being so positioned that cutting edge 27 of the blade, will cut through the walls of the box at the lower edge of the recesses previously 120 formed in the inner surfaces thereof.

The depth of the cut is limited by the abutment of the sides of the box against the periphery of cutter head 17, the cutting edges of the blade projecting beyond said cutter head to such a distance that front cutting edge 28 will cut all the way through the walls of the box so as to separate the lid from the box proper, the cutting edge 27 making a finished cut upon the lower 125 130

edge of the lid which is recessed at its inner side by the concave surfaces 24.

At the same time cutting edge 27 cuts only part way through the walls of the box 5 so as to form bead 31 having a convex surface at the inner portion of the upper edge of the box proper, and cutting edge 30 forms an offset shoulder 32 in the outer portion of said upper edge of the box proper 10 at the base of the bead, as shown at the right of Fig. 4.

It will thus be seen that when the lid has been cut from the box proper, the walls of the box and its lid are provided at their 15 inner sides with a vertically alined cooperating bead and recess, and at their outer side with a cooperating shoulder and finished lower edge, the cutting blades having their edges so arranged that said bead 20 and recess will have corresponding convex and concave surfaces, in order to provide a tight joint when the lid of the box is closed, while permitting face swinging of said lid without abutment of the same 25 against said bead.

After the lid has been cut from the box proper as thus described, it may be hinged thereto in usual manner to form the finished box shown in Fig. 6.

30 In the modification of the invention illustrated in Fig. 7, the walls of the assembled box structure are cut by a blade having cutting edges 27, 28, 29, and 30, adapted to make a cut as previously described, and 35 also having cutting edges 33 and 34 at the rear ends of edges 27 and 30, respectively.

The cutting edges 33 and 34 are so shaped as to cut any desired molding in the outer surfaces of the side walls and top of the 40 box, at the same time that the lid is cut from the box proper and the bead and shoulder are formed at the upper edge of the latter.

By this arrangement it will be seen that 45 a molding may be cut upon the box without increasing the number of operations in the manufacture thereof.

We claim:

1. The method of constructing a container 50 consisting of assembling a closed structure adapted to form a box proper and its lid, and cutting part way through the sides of said structure and all the way through said sides at one edge of said partial cut at one operation, so to form separated box proper and lid members having an offset bead as an integral part of the edge of one of said separated members.

2. The method of constructing a container 60 consisting of assembling a closed structure adapted to form a box proper and its lid and having a recess in the inner faces of its sides, and cutting from the exterior of said structure all the way through said sides at one edge of said recess 65 and part way through said sides next to said severing cut and beyond said recess at one operation, so as to form separated box proper and lid members having an inwardly offset bead as an integral part of 70 the edge of one of said members, and a recess in alinement with said bead in the edge of the other of said separated members.

3. The method of constructing a container 75 consisting of cutting recesses in one side of strips of material, assembling said strips so as to form the side walls for a box proper and its lid with said recesses in the inner faces of said side walls, fixing a top and bottom on said side walls, and cutting into the outside of said side walls with the upper portion of said cut extending through said side walls at the lower sides of said recesses and the lower portion of 80 said cut extending below said severing cut 85 and only part way into said side walls to a point in vertical alinement with the bases of said recesses, so as to form a separated box proper and lid members having an upstanding bead as an integral part of the inner side 90 of the upper edge of the box proper, and a recess in vertical alinement therewith in the inner side of the lower edge of the lid, with an offset shoulder in the outer side 95 of the upper edge of the box proper at the base of said bead and in vertical alinement with the outer side of the lower edge of the lid.

4. The method of constructing a container 100 consisting of assembling a closed structure adapted to form a box proper and its lid, and cutting part way through the sides of said structure and all the way through said sides at one edge of said partial cut and also cutting a molding in the 105 surfaces of said sides at one operation, so as to form separated box proper and lid members having molded surfaces and also having an offset bead as an integral part of the edge of one of said separated members. 110

In testimony whereof we have affixed our signatures.

LOUIS M. DANKLEFS.
